UNITED STATES PATENT OFFICE

2,573,640

DIGGING DEPTH INDICATOR FOR BORING MACHINES

George H. Connors, Edgerton, Wis., assignor to
Highway Trailer Company, Edgerton, Wis., a
corporation of Delaware

Application January 14, 1948, Serial No. 2,304

7 Claims. (Cl. 255—22)

1

My present invention pertains to the art of earth boring and pole setting means of the type employing an adjustable boring head supporting a boring bar or shaft carrying an auger by which the hole digging operation is performed.

My invention comprises an improved type of digging depth indicator for machines of the class above referred to, and particularly digging depth indicating means adapted for the construction of such machines as disclosed in the patent of Spowart, No. 1,511,433, issued October 14, 1924, and Erdahl, No. 1,921,812 issued August 8, 1933.

In earth boring machines of the type disclosed in the above identified patents, the boring bar or shaft which carries at its lower end the auger which does the hole digging work is surrounded by a tube or vertical casing leading upwardly from and attached to the boring head, this tube being utilized to steady the upper end of the boring shaft or bar while it rotates the auger, thus preventing whipping of the said upper end of the boring bar as it is driven to effect the earth digging operation in making a hole. This above mentioned tube that surrounds the boring bar or shaft additionally performs the function of a derrick boom commonly used in conjunction with suitable winch and cable means for facilitating the pole setting operation, or the emplacement of the pole in the hole dug by the auger after the digging operation has been completed.

Since the stabilizing and boom tube or casing above referred to completely encloses the upper portion of the boring bar or shaft in the digging operation, in the use of present machines of the type referred to and disclosed by the patents above identified, it is necessary for the operator to estimate the depth to which the auger has penetrated the ground, and necessarily this is difficult to do because the boring head and the boring bar carried therein and thereby are frequently adjusted to different angular positions transversely and longitudinally of the machine chassis by which they are supported, preliminary to the digging operation. These angular adjustments are necessary because at times the machine is disposed over uneven ground either inclining transversely to the machine or longitudinally of the machine chassis, making necessary the angular adjustment in order to bring the boring bar and its auger into a true vertical position for digging a vertical hole.

To avoid the uncertainty incident to the estimating of the depth to which the auger penetrates the earth, and the resultant loss of time involved in measuring the hole back-filling, or

2

effecting additional boring and re-measuring, I have developed the depth indicating means of my present invention for use in connection with machines of the class described.

With the foregoing objectives in mind, my depth indicator comprises primarily an indicating wheel containing indicia for measuring. Said indicating wheels operated by cable means which are connected to the upper end of the boring bar through a side of the enclosing tube or casing before mentioned, so that the cable of said means is pulled to an extent proportionate with the degree of movement of the boring bar and the auger which it carries, as the auger penetrates the ground. The cable of said cable means is attached to a reel in order to compel a rotating movement of the reel and its shaft during the digging movement of the boring bar and auger, and means are provided for operating the indicating wheel from the cable reel. Additionally, I make provision for operator adjustment of the indicating wheel to pre-set the same always to a zero position independently of its actuation from the cable reel so that the indicating action of the indicating wheel may be caused to start, after the auger has been operated by the boring bar to bring the point of the auger into engagement with the ground, at which time it starts digging. Other features of detail pertaining to my invention, rendering the same practical for the purposes hereinbefore stated, will be more fully presented in the following description, to be read in conjunction with the accompanying drawings, in which:

Figure 1 is a view in side elevation showing partially the chassis or mobile supporting means of an earth boring and hole setting machine of the type to which my invention relates, said machine having the boring mechanism mounted upon the rear end thereof, as customary, and those portions of the boring mechanism to which my invention relates, only, being illustrated, with the invention applied thereto.

Figure 2 is a rear end view of the machine as shown in Figure 1.

Figure 3 is an enlarged view bringing out more clearly the details of my mechanism as mounted on the upper portion of the boring head and the lower portion of the tube or casing which surrounds the boring bar.

Figure 4 is a side view largely of the parts shown in Figure 3, with certain of said parts broken away and shown in section to render these same more clear.

Figure 5 is a detail sectional view bringing out

more fully the connection of the adjusting knob for the indicating hand which is carried by the shaft of the reel about which the cable winds, said cable connected with the upper end of the boring head.

Figure 6 is a detail view in rear elevation of the indicating wheel, the indicia of which is provided on the front or outer side of the wheel, this view showing the detent recesses in the rear side of said wheel.

Figure 7 is a partial sectional view showing detail construction of the winding reel or drum for the cable means.

Referring to the accompanying drawings, the machine to which my invention is applied is partly illustrated in said drawings as including a chassis or frame 1 mounted on wheels 2, or the chassis may be supported by crawlers, if desired. Carried at the rear end of the chassis 1, usually, is the hole digging or boring mechanism which includes primarily the boring head 3 supported by suitable mounting means 4 and containing the drive gearing by which the boring bar or shaft 5, a portion of which is seen at the top broken-away part of Figure 2, is operated. The boring shaft or bar 5 is adapted to move downwardly and upwardly in the tubular guide or boom 6a which is suitably attached to the top of the boring head 3, and as the bar 5 is driven in a downward direction, rotation is imparted thereto by suitable gear mechanism within the head 3, all as well known in the art.

It is notable that the boring head 3 is adapted to be turned or partly rotated about an axis transverse to the longitudinal axis of the frame or chassis 1 in order that the auger 6 carried by the lower end of the bar 5 may be shifted outwardly and inwardly relatively to its vertical position as seen in Figure 1, in a plane longitudinally of the chassis 1. The transverse axis point for such movement is generally indicated by the dotted line arrow A in Figure 1.

Additionally the boring head 3 is capable of being rotated to different angles laterally relatively to the chassis 1, as it is viewed in Figure 2, under which conditions the head operates about the longitudinal axis relatively to the frame 1 which longitudinal axis is generally indicated by the dotted arrow B in Figure 2. The auger 6 is a conventional type of auger rigidly secured to the lower end of the boring bar or shaft 5. At the top of the tubular guide or what I call the boring bar tube or casing 6a there is mounted by suitable axis means a sheave or pulley 7, and usually a cable extends over this pulley, which cable at one end is equipped with a hook for facilitating tying the same about a telegraph or telephone pole. At the opposite end the cable leads to a winch suitably supported on the mounting means 4, but not shown, said cable and hook means also being omitted from the illustration because conventional.

Generally speaking, the foregoing characterizes the construction of the parts of a boring machine in conjunction with which my invention is readily to be used or applied, said machine as to all main operating and supporting features being more fully disclosed in the Erdahl patent previously mentioned above.

It is obvious that if the boring head 3 is in the position in which it is shown in Figures 1 and 2, under the conditions of the ground supporting relation between the chassis or frame of the supporting vehicle and the ground level as depicted in these figures, the point of the auger

6 will engage the ground for digging action after a relatively small movement of approximately a few feet. Obviously, however, should the vehicle supporting the machinery hereinbefore described be on an elevated ground level while the hole to be bored is some distance down below such level, at a bank for instance, the auger 6 will have to travel a considerable distance more than would be the case according to the showing of Figures 1 and 2, before engaging the ground to start digging. The latter condition is also true if the boring head 3 is adjusted so that it lies at a lateral angle to the level chassis or a longitudinal angle, dependent upon the conditions of service.

My indicating means of my present invention is designed and constructed, therefore, to deal with the conditions of variability of distance of location of the auger point in relation to the earth level at which said point will start its digging operation, the variances of course being due to the adjustment of the position of the boring head 3, and whether the auger point is required to move different distances from its normal positions of Figures 1 and 2 incident to the particular job of earth boring which has to be performed.

I now describe the depth indicating means that forms the special feature of my present invention as employed in combination with boring machines of the type above set forth.

The boring bar 5 is equipped at its upper end with a guide head 8, and for the purposes of my invention I provide this head mounted swivelly on the boring bar 5. The head 8 is equipped with a loop or eye 9 at its upper portion and a cable 10 is attached to said eye 9 and extends laterally from the head 8 through an opening in the side of the tubular guide 6a, over a pulley 11 attached near the upper outer portion of said member 6a. From the pulley 11 the cable 10 leads downwardly to a reel casing 12 supported near the lower end of the guide member 6a upon a reel shaft 13, a suitable supporting frame 14 being supplied for a mounting means for the reel or drum about which the cable 10 is adapted to wind and from which the cable may unwind, as hereinafter described. On the reel shaft 13 I provide a trip arm 15, see Fig. 3, having a pointer 16 integral therewith, the pointer 16 having an opening near its inner end which is mounted upon the reduced portion 13a of the shaft 13 and adapted to abut the shoulder 13b adjacent said reduced portion 13a. A thumb nut or equivalent member designated 17 is employed to tighten or clamp the trip arm 15 in position so as to turn or rotate with the shaft 13 for a purpose to be shortly seen. On the outer end of the reel casing or housing 12 which is substantially circular, I provide measurement indicia designated 18 comprising preferably the markings $\frac{1}{4}$, $\frac{1}{2}$, $\frac{3}{4}$, these indicia being related to dimensions in terms of feet of movement of the cable 10 and correspondingly the boring bar 5.

Below the reel or drum unit just described, to which the outer end of the cable 10 is secured is located a casing 19 in which is mounted the indicator wheel 20, in the back of which are provided a series of detent recesses 21, twelve in number as shown, with which recesses there cooperates a detent plunger 22 spring pressed by a spring 23 to enter the recesses 21 of the indicator wheel 20, as the latter rotates.

On its peripheral portion the indicator wheel 20 has a number of equally spaced projections

or lugs so disposed that they are located one at a time in the path of swinging movement of the arm 15 incident to its rotation about the axis of the shaft 13. On its outer face the wheel 20 bears indicia in the form of numbers from "0" to "11." The indicator wheel 20 is mounted upon a shaft 24 to which it is keyed for turning therewith and the shaft supports the wheel 20 by being mounted to turn freely in bearing portions 25 and 26 formed in the sides of the casing 19. At its outer side the casing 19 has a vision opening 27 through which the numbers or indicia on the outer face of the wheel 20, designated at 28, may be seen as each number is brought to a position opposite to said opening 27. At its inner end the shaft 24 is prevented from displacement outwardly by means of a collar 29 held in place by a cotter pin passing through the shaft and said collar, and at its outer end the shaft 24 is prevented from inward displacement by means of the handle 30 which is keyed to the shaft and prevented from accidental displacement by means of the nuts 31 threaded on the outer end of the shaft 24.

It is noted that the outer end of the bracket mounting 14 for the cable reel or drum, on the shaft 13, is provided with a "zero" indication designated 32, this indication cooperating with the indicating pointer 16 as will now be described.

The operation of my depth indicating means will be readily understood from the foregoing description of the construction of the various parts, and I set forth said operation as follows. It may be assumed for purposes of this description that the chassis or frame of the vehicle comprising the members 1 and 2 is located on an incline so that the front end of the vehicle is downwardly inclined, thereby elevating the boring head 3 and adjuncts supported thereby. Under these conditions, in order to start the digging of the hole, the operator will adjust the boring head 3 angularly in a plane longitudinally of the chassis 1 until said head stands substantially vertical with its casing or guide tube 6a similarly disposed. By operating the boring bar 5 in the usual manner, the same is rotated and lowered until the point of the auger 6 contacts with the earth. It will be assumed that a hole five feet is to be dug. During the lowering of the boring bar to position the auger 6, as stated, the cable 10 will be pulled downwardly by the head 8 at the top of the bar 5, and therefore unwound from the reel or drum on the shaft 13 for a certain number of feet or fractions of feet, dependent upon the distance of the point of the auger 6 from the ground point at which the hole is to be dug. During the adjusting or lowering of the point of the auger 6 in the manner stated, the operation of the indicating wheel 20 will be ignored. As soon, however, as the point of the auger 6 reaches the ground level the operator will temporarily stop the downward feed of the boring bar 5, and while the feed is discontinued, the operator will turn the indicating wheel 20 to the zero position shown in Figure 3. At the same time he will adjust the trip arm and pointer 15-16 to its preliminary tripping position as shown in Figure 3 also. The trip arm 15 is now ready upon unreeling of one foot of the cable 10 from the reel or drum on the shaft 13 to strike the uppermost projection 33 on the indicator wheel 20 and turn said wheel sufficiently to bring the indication "1" in front of the vision opening or window 20-27. Thus it is that once the parts have been adjusted in

the manner shown in Figure 3, at the time the point of the auger has reached the ground surface and is ready to dig the hole, the operator then throws in the drive gearing for feeding the boring bar 5 and the auger 6 downwardly into the ground, and on each revolution of the reel or drum of shaft 13 incident to the unwinding movement of the cable 10 pulling on said drum and rotating same the arm 15 will trip the indicator wheel 20 to impart thereto one-twelfth of a revolution, this increment of movement indicating a foot of digging depth performed by the auger 6. In the present instance the hole to be made by the auger being intended to be five feet deep, when the indicia "5" appears at the opening 28, effected by the arm 18 having rotated five times and imparted five increments of movement to the wheel 20, the operator will stop the boring or digging operation of the auger 6 and will know positively that a hole of 5' in depth will have been bored into the earth being penetrated.

It will be understood, of course, that the operation of adjusting the wheel 20 to "0" is effected by turning the wheel shaft 24 and wheel 20 by grasping the handle 30. The adjustment of the pointer 15 is of course effected to bring it to its zero position as shown in Figure 3, at the time of the starting of the digging action of the auger 6 by loosening the thumb nut 17 manually positioning the arm 15, and then re-tightening the thumb nut 17 so that the arm will turn with the shaft 13.

Under some conditions, of course, it may be desirable to bore the hole distances comprising fractions of a foot, it being borne in mind that the indicia on the indicator wheel 20, as to each number, is intended to be shifted one increment incident to each revolution of the reel on the shaft 13, it being evident that the arm 15 likewise makes one revolution as the cable 10 unwinds one foot from the drum on the shaft 13. Therefore, by the provision of the indicia 18 on the end of the casing 12 of the reel, and the zero indication 32 on the frame part 14 adjacent to the outer end of the reel, the operator may readily note when the pointer 16 of the arm 15 reaches a position indicating a one-fourth foot movement of the cable 10, and correspondingly the boring bar 5 and auger 6, a one-half foot extent of movement, or a three-quarters foot extent of movement. This enables the operator to control digging depths with accuracy in increments of quarter-foot movements of the boring tool 6, in an obvious manner.

The reel or drum on the shaft 13 is an ordinary spring actuated drum and the cable 10 is wound thereon by the spring means as the boring bar 5 is moved in guide 62. The detent 22 is ineffective to prevent the spring controlled cable re-winding action of said drum. The details of the spring drum 37 are seen in Figure 7 wherein the shaft 13 that is keyed to turn with the drum is shown mounted on one side of the frame 14. It is a short shaft, and, mounted stationary on the opposite side of the frame by a pin 35, is a short shaft 36, coaxial with the shaft 13, and providing a bearing for the inner portion of the drum or reel 37, and an inboard support for the casing 12. A helical spring 38 in the drum 37 is fixed at its inner end at 39 in a slot of the stationary shaft 36, and at its outer end fixedly pinned at 40 to the inner periphery of the drum 37. The spring 38 is normally tensioned to cause the cable 10 to wind onto the drum 37 when the

load on the cable 10 is relieved when the auger is raised.

Having thus described my invention, what I claim as new and desire to secure by Letters Patent of the United States, is:

1. In a boring machine, in combination, a boring bar, an auger at the lower end of said bar, a boring head for the bar and operating means in the head to raise and lower the bar and its auger, a digging depth indicating unit comprising an indicator exteriorly arranged relatively to the head, a cable drum on the boring head, a trip arm operable by the drum and coacting with the indicator to move the latter a predetermined distance corresponding with the movement of the boring bar, and a cable connecting the boring bar with said drum.

2. A machine as claimed in claim 1, combined with a casing for the drum having distance measuring indicia thereon, and means on the trip arm coacting with the indicia on said casing to supplement the indicating action of the indicator tripped by the trip arm in measuring the distance of movement of the boring bar.

3. A boring machine comprising a support, a boring bar, an auger at the lower end of the bar, a boring head adjustable on the support to shift the bar and auger relatively to the ground to position same for digging action, an indicator on the boring head for measuring the distance of digging movement of the boring bar and auger, actuating means between the boring bar and the indicator, and manually operable means to adjust the indicator to different starting indicating positions, relatively to said actuating means, when the digging end of the auger contacts the ground preliminary to digging.

4. A machine as claimed in claim 3, in which the actuating means includes a trip arm movable by means connected to the boring bar for operating the indicator, said arm being manually adjustable for pre-setting the same in an initial operating position relatively to the indicator.

5. In a boring machine, in combination, a support, a boring bar, an auger at the lower end of said bar, a boring head for the bar adjustable on the support so as to bring the digging end of the auger to different distances from the ground, and operating means in the head to raise and lower the bar and its auger, a guide coacting with the bar to direct the movement of the bar and carried by the head, a digging depth indicating unit comprising an indicator exteriorly arranged relatively to and on the head, operating means between the indicating unit and the bar to cause indicating movement of the indicator as the bar is lowered in the guide to measure the distance of the movement of the bar, said second operating means leading from and attached to the upper end of the boring bar, said means including actuating instrumentalities external to the boring head for moving the indicator, said instrumentalities comprising a rotating arm, a cable drum connected to turn said arm, and the indicator comprises movement measuring devices arranged to be shifted by the arm as it turns, and a cable leading from the drum and connected to the boring

bar to be actuated by the latter, said cable being reeved over a pulley mounted in the guide.

6. In a boring machine, in combination, a support, a boring bar, an auger at the lower end of said bar, a boring head for the bar adjustable on the support so as to bring the digging end of the auger to different distances from the ground, and operating means in the head to raise and lower the bar and its auger, a guide coacting with the bar to direct the movement of the bar and carried by the head, a digging depth indicating unit comprising an indicator exteriorly arranged relatively to and on the head, operating means between the indicating unit and the bar to cause indicating movement of the indicator as the bar is lowered in the guide to measure the distance of the movement of the bar, said indicating unit comprising a cable drum, and the second operating means including a cable leading from the drum through the guide near its upper end, and manual means to pre-set the indicator independently of its movement by the cable for measuring the distance of movement of the boring bar from a preset position at which it engages the ground.

7. In a boring machine, in combination, a support, a boring bar, an auger at the lower end of said bar, a boring head for the bar adjustable on the support so as to bring the digging end of the auger to different distances from the ground, and operating means in the head to raise and lower the bar and its auger, a guide coacting with the bar to direct the movement of the bar and carried by the head, a digging depth indicating unit comprising an indicator exteriorly arranged relatively to and on the head, operating means between the indicating unit and the bar to cause indicating movement of the indicator as the bar is lowered in the guide to measure the distance of the movement of the bar, the said second operating means leads from and is attached to the upper end of the boring bar, and includes actuating instrumentalities external to the boring head for moving the indicator, said instrumentalities comprising a rotating arm, a cable drum connected to turn said arm, and the indicator comprising movement measuring devices arranged to be shifted by the arm as it turns, a cable leading from the drum and connected to the boring bar to be actuated by the latter, and manual means including a handle connected to said arm to move the indicator independently of the drum and arm to pre-set said indicator.
